NUT LOCK

Andrew J. Earley, Cambria, Va.

Application June 6, 1940, Serial No. 339,187

2 Claims. (Cl. 151—8)

This invention relates to an improved form of nut lock and more particularly to an improved construction of latch element for keying a nut to a bolt, and to improved means for mounting the latch element to the shank portion of a bolt.

It is a particular aim of the invention to provide a construction of nut lock wherein the latch element may be readily retracted and held in a retracted position by means of a pointed instrument, such as a nail, so that the nut may be turned freely on the threaded portion of the shank in properly adjusting it relatively thereto after which the pointed instrument may be withdrawn for releasing the latch element to permit it to move into an operative position for keying the nut to the bolt.

Other objects and advantages of the invention will hereinafter become more fully apparent from the following description of the drawing, which illustrates a preferred embodiment of the invention, and wherein:

Figure 1 is a side elevational view of the invention,

Figure 2 is an end view in elevation of the same,

Figure 3 is a side elevational view, partly in section, taken substantially at a right angle to Figure 1, and

Figure 4 is a transverse sectional view taken substantially along the plane of the line 4—4 of Figure 3.

Referring more particularly to the drawing, wherein like reference characters designate like or corresponding parts throughout the different views, 10 designates generally a bolt having a shank 11 which is threaded at 12, adjacent its outer free end. The shank 11 is provided with a slot 13 which extends from adjacent its outer end inwardly thereof to a point beyond the threaded portion 12. The shank 11, at its outer end, is provided with an opening 14 which is of substantially the same width as the slot 13 and which extends inwardly from its free end and communicates with the outer end of the slot 13. The slot 13 and the opening 14 combine to form an abutment 15 which closes the outer end of the slot 13, at its outer edge.

The slot 13 is relatively deep and relatively narrow to receive the elongated blade portion 16 of a latch element 17 which extends substantially the length of the slot 13 and which is loosely disposed therein. The blade 16, at its inner end, is formed integral with an arm 18 which projects transversely therefrom through an open-

ing 19, in the shank 11, which communicates with the slot 13 at its inner end. The free end of the arm 18 is provided with a head 20 which is countersunk in the periphery of the shank 11 at the outer end of the opening 19 for securing the latch element 17 at one end thereof in the shank 11. The blade 16 is relatively wide and relatively thin and tapers in width from its outer, free end to its inner, secured end. The slot 13 is of substantially the same depth throughout its length which depth is slightly greater than the width of the widest portion of the blade 16. Blade 16 at its outer end is provided with an extension 21 which projects from its inner edge through the opening 14. The opening 14, at its edge opposite to the abutment 15, is cut on an angle, as seen at 22 to increase the width of the opening 14. The blade portion 16 is formed of resilient material, such as spring metal, and is urged outwardly of the outer edge of the slot 13, by this resiliency. The outward movement of the blade portion 16 is limited by the extension 21 engaging the inner side of the abutment 15, and when thus positioned, as seen in Figure 3, the outer edge of the blade 16 projects beyond the outer, open edge of the slot 13. The blade portion 16 can be retracted by engaging the extension 21 and moving it toward the edge 22 of the opening 14 to move the blade 16 inwardly of the slot 13 sufficiently, so that it is entirely disposed within said slot.

When thus positioned, a nut 23, having a threaded bore 24, may be applied to or removed from the threaded portion 12 or adjusted relatively thereto. The threaded bore 24 is provided with a plurality of spaced grooves 25, which extend across the thread of the bore 24 so that when the blade 16 is released from a retracted position to spring outwardly, it will engage the thread of the bore 24. By then turning the nut 23 one of the grooves 25 will be aligned with the slot 13 to permit the outer edge of the blade 16 to move outwardly and into engagement with this groove 25 to thereby key the nut to the threaded portion 12 to prevent it from being turned relatively to the bolt 10 until the blade portion 16 is again retracted, as heretofore described. In order to enable the nut 23 to be turned freely relatively to the threaded portion 12 of the shank 11, the blade 16 may be retracted, as heretofore explained, after which a pointed instrument such as the pointed end of a nail can be inserted into the opening 14 between the abutment 15 and the extension 21 to

effectively retain the latch element 17 in its retracted position to enable the nut 23 to be freely adjusted on the shank 11, removed therefrom or applied thereto, after which the nail or pointed instrument, not shown, can be withdrawn to permit the blade 16 of the spring latch element 17 to spring outwardly for engaging one of the grooves 25.

Various modifications and changes are contemplated and may obviously be resorted to as only a preferred embodiment of the invention has been disclosed.

I claim as my invention:

1. In combination with a bolt having a longitudinal slot, and a resilient latch blade disposed in the slot and anchored to the bolt at its inner end and adjacent the inner end of the slot; an abutment forming a part of the bolt and bridging the outer portion of the slot,

the outer end of the blade being loosely disposed in the slot and urged outwardly thereof, in a direction laterally of the bolt by the resiliency of the blade, and an extension on the free end of the blade, said extension being disposed inwardly of said abutment and normally in engagement therewith for limiting the outward movement of the latch blade, one longitudinal edge of the blade being disposed outwardly of the slot when the extension is in engagement with said abutment.

2. A device as in claim 1, said last mentioned end of the slot opening outwardly of an end of the bolt, and said extension projecting beyond said end of the bolt and being adapted to be manually engaged and actuated for retracting said longitudinal edge into the slot.

ANDREW J. EARLEY.
